Victor J. Evans
ATTORNEY

UNITED STATES PATENT OFFICE.

WALTER STINE, OF BARBERTON, OHIO.

TRAIN CONTROL.

Application filed May 23, 1921. Serial No. 471,700.

To all whom it may concern:

Be it known that I, WALTER STINE, a citizen of the United States, residing at Barberton, in the county of Summit and State of Ohio, have invented new and useful Improvements in Train Controls, of which the following is a specification.

This invention relates to automatic train stops, and comprehends the construction by means of which the brakes will be gradually applied to stop the train without any jerking of the latter, and at the same time operate the throttle to shut off the steam, the invention residing in the construction, combination and arrangement of parts as claimed.

In the drawings forming part of this application, like numerals of reference indicate similar parts in the several views and wherein:

20 Figure 1 is a fragmentary sectional view through the train control apparatus, showing the normal position of the parts.

Figure 2 is a sectional view taken on line 2—2 of Figure 1.

25 Figure 3 is a view similar to Figure 1, showing the active position of the parts.

Figure 4 is a view, partly in section, of a modified form of the invention.

30 Figure 5 is a top plan view of the piston and piston rod.

Referring to the drawings in detail, 10 indicates a cylinder which is adapted to be bolted or otherwise suitably secured to the locomotive (not shown), the cylinder being closed at both ends with the upper end provided with an opening through which the piston rod 11 reciprocates. The piston rod supports spaced pistons 12 and 13 respectively, while surrounding the piston rod 11 is 35 a coiled spring 14, the latter being tensioned to bear against the adjacent piston and the upper end of the cylinder, to normally hold the pistons in the position illustrated in Figure 1. The piston rod 11 slides through

40 an opening in the bottom of the cylinder and carries at its lower end a shoe 15 which is threadedly secured thereto and is adapted to engage the ramp rail 16 when the latter is set for use, it being understood that as the shoe passes over the ramp rail, the piston rod together with the pistons are shifted to the 45 position illustrated in Figure 3 against the tension of said spring. A conduit 17 communicates with the cylinder 10 at a point adjacent the bottom thereof and establishes

communication between the train line pressure and the cylinder between the pistons 12 and 13. The cylinder is provided with an exhaust port 18 adjacent the lower end thereof, which port is considerably smaller 60 than the inlet port with which the conduit 17 communicates. Leading from the lower end of the cylinder is a pipe 19 which is associated with a whistle or other suitable signal 20, the latter being actuated by the 65 pressure which passes through the pipe 19 from the cylinder 10. A branch pipe 21 projects from the pipe 20 and establishes communication between the latter and a cylinder 23 supported by the branch pipe 21. 70 This cylinder forms a part of the locomotive control device, and embodies a piston 24 which operates within the cylinder 23, the piston rod 25 reciprocating through the opening 26 in one end of the cylinder and 75 extended for operative association with the throttle valve (not shown). A coiled spring 28 surrounds the piston rod 26 and normally holds the piston adjacent that end of the cylinder next to the branch pipe 21. 80

Normally, the parts are arranged in the manner illustrated in Figure 1, wherein the piston 13 closes the exhaust port 18 and the adjacent end of the pipe 19. The pressure from the train line is then conveyed to the 85 cylinder 10 and between the pistons 12 and 13. When the shoe 15 passes over the ramp rail 16, the pistons are moved upwardly in the cylinder 10 to the position illustrated in Figure 2, and the pressure in the air line 90 is then allowed to exhaust to the port 18 causing the brakes to set on the train, in a manner which will stop the train gradually, without any unnecessary jerking. A portion of the train line pressure also escapes 95 through the pipe 19 to operate the signal 20, and to also actuate the piston in the cylinder 23, which is connected with the throttle valve, thereby shutting off the steam. The device is not only simple in construction 100 but is very positive and efficient for the purpose intended.

In Figure 4, I have illustrated a modified form of the invention wherein the cylinder 10' is constructed similarly to the cylinder 10, except that the exhaust port 18 is eliminated. The conduit 17' leads into the cylinder 10' in the same manner as illustrated in Figure 1, while the piston 13' normally closes the adjacent end of the pipe 19' which 110

leads from the lower end of the cylinder 10'. The pipe 19' supports a whistle or other signal 20' at the upper end thereof, the latter being actuated by the pressure from the cylinder passing through the pipe 19'. In this form of the invention, two branch pipes 21' and 22' project from the pipe 19', and each of the branch pipes supports a cylinder 23' as illustrated. A spring pressed piston 10 (not shown) operates within each of the cylinders 23', the piston rods 24' projecting from their respective cylinders, and operatively connected in any suitable manner to the throttle valve, and to the brake control lever in the locomotive, so that the steam is automatically cut off and the brakes automatically applied incident to the exhaust passing through the pipe 19' and entering the cylinders 23'. Otherwise, the construction shown in Figure 4 operates in the same manner as that shown and described in conjunction with the preferred form of the invention.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What is claimed is:

An automatic train control comprising a cylinder provided with openings in the upper and lower ends thereof, a piston rod adapted to reciprocate within the cylinder and having its respective ends passing through said openings, spaced pistons carried by the rod and arranged intermediate

of its ends, a coil spring surrounding the rod and having its end convolutions bearing against the adjacent piston and the upper end of the cylinder and said spring being adapted to hold said pistons in a normal position, a shoe threadedly secured to the lower end of said rod and adapted to engage a ramp rail of the system at predetermined times, a conduit establishing communication between the train line pressure and said cylinder and designed to communicate with said cylinder at a point between the normal position of said pistons, said cylinder having an exhaust port in its cylindrical wall adjacent the lower end thereof, and said port being normally closed by the adjacent piston, a pipe leading from the cylinder at a point opposite to the exhaust port, a signal carried by the opposite end of said pipe and adapted to be actuated by the pressure passing through said pipe from the cylinder, a branch pipe leading from the last mentioned pipe adjacent and below said signal, a second cylinder supported by the branch pipe which communicates therewith, said last mentioned cylinder being arranged at an angle with respect to the first mentioned cylinder, and provided with an opening directly opposite the communication end of the branch pipe, a spring pressed piston adapted to operate in the second cylinder, and a rod entering the opening in the second cylinder and having one end secured to the adjacent end of said piston and its opposite end extended for operative association with the throttle valve of the train as and for the purpose specified.

In testimony whereof I affix my signature.
WALTER STINE.
